UNITED STATES PATENT OFFICE

HOBART B. BROWN, OF CEDAR FALLS, IOWA

HEAT CONTROLLING MEANS FOR FURNACES

Application filed February 1, 1932. Serial No. 590,146.

My invention relates to heat controlling means for furnaces, and the object of my improvement is to supply for heating furnaces of various descriptions having draft doors and dampers, coacting means for reversely opening and closing them simultaneously, such means being operatively controlled by thermostatic means inserted in the furnaces where they are subjected to internal heat thereof.

Another object is to furnish such means for mounting them adjustably upon a furnace.

I have accomplished the above objects successfully in actual reduction to practice, by the devices which are hereinafter described and claimed, and which are illustrated in the accompanying drawing, in which Fig. 1 is a side elevation of a conventional hot air furnace, having my improved thermostatic device with draft door and damper operating connections and elements and according to my invention. Fig. 2 is an enlarged side elevation in detail of my said thermostatic device including the compound helical spring thereof as adjustably mounted upon a furnace casing. Fig. 3 is an outer front elevation thereof with operating arm removed. Fig. 4 is a front elevation of said operating arm as mounted upon the outer end of the thermostat shaft. Fig. 5 is a side elevation of the device, without said arm, but including a spiral spring of compound construction. Fig. 6 is a magnified cross section of either of said types of springs as used in the invention.

The numeral 1 denotes a conventional furnace having at the rear the usual flue 2 equipped with a hinged damper 3, and at the front an ash-pit door 4 having thereon a smaller draft door 5 hinged thereto. Upon a rafter 7 overhead a pair of pulleys 8 and 9 are mounted dependingly, and carry the reach of a flexible cable 10, or chain if desired, one end of which is connected to the damper 3. As usual the furnace casing has a conic frustum top 6 provided with a lateral aperture traversed by a rock-shaft 11. Referring to said Figs. 1 and 2, this shaft is mounted

horizontally and yet adjustably upon the inclined wall 6 in the following way.

Secured to the inclined wall 6 as by screws is a centrally apertured bearing plate 21 covered by a coacting plate 22 secured by screws 27 thereto, the coinciding hollows whereof constitute a spherical bearing hollow for the contained spherical part 24 of a sleeve member with slightly coned ends 25 and 26, and loosely mounted on the shaft 11. By loosening the screws 27, the part 24 may be freely rotated adjustably, to permit of positioning the shaft 11 in a horizontal direction, and the outer member 22 serves as a clamping means upon the part 24 when the screws 27 are tightened to lock it in place, the shaft thus being maintained horizontal on differently inclined walls 6 of furnaces.

Upon the shaft 11 within the furnace casting above a firebox dome not shown, is mounted in Fig. 1 a helical band spring 28. The inner termination of the shaft is split to receive therein an end of said spring which is secured by a cross rivet 30. The sleeve part 26 has a boss 29 with opposite parallel faces, the other termination of the spring being fastened upon one face thereof by a rivet 28'.

Referring to Fig. 4, the numeral 14 denotes an arm fixed by a set-screw at 12 upon the outer end of the shaft 11 and has a counterweight 13. The outer end of the arm 14 is forked at 15 with its furcations crossed by a pintle carrying a depending block 17 and sheave 18. As shown in Figs. 1 and 4, a sheave 16 is mounted rotatably on the shaft 11 within a cavity of the arm 14. The arm 14 has a longitudinal flange 19 with a longitudinal row of holes 20. The forward depending end part of the cable 10 is secured in any hole 20 of said flange adjustingly to permit adjustments of throw of the draft door 5. In Fig. 6 is shown in cross section and with an enlarged scale the spring 28, likewise the spring 32 of Fig. 5, being registering and united bars or plates made of metals having different coefficients of heat expansion and contraction, which vary the action of the spring in rotating the shaft 11.

The arm shown in Fig. 4, besides the ad-

justable connecting means for the cable 10, has thereon the sheave 18 and the other sheave 16 on the shaft 11 in cooperation for carrying the reach of another cable (or chain) 5 as at 40 reeved about the sheaves and end-connected at its lower end to the draft door 5 on the ash-pit door 4. The upper termination of the cable 40 is passed upwardly through an aperture in the floor above and supplied with an end ring 42 to be engaged with a wall pin above to hold the draft door open by manual operation when desired. This does not interfere with the automatic action of the devices previously described.

15 The spring 28 is by the varying heat within the furnace casing, expanded or contracted to correspondingly rotate the shaft 11 forward or back, and by way of the cable 10 the draft door 5 is more or less held open in its scope 20 of movement, or held closed or entirely open, the cable acting upon the draft door and the damper 3 reversely in opening and shutting them, and automatically.

25 The modification of said Fig. 5 shows the substitution of a spiral spring 32 which operates the shaft 11 similarly, but permits the use of a shorter shaft 11, so that the latter may be installed within a furnace casing having only a small amount of clearance for the 30 shaft. The spring 32 has its inner termination clamped within the split or forked termination of the shaft, and its outer end 33 is bent outwardly and fastened to a lug 34 on the sleeve bearing 35 by a screw 39, the 35 forks 31 of the shaft being drawn together by a rivet 38 to clamp the inner inserted end of the spring.

Having described my invention, what I 40 claim as new, and desire to secure by Letters Patent, is:

1. In combination, a furnace having a draft door and a damper, a thermostatic device within the furnace consisting of a rock-shaft traversing the furnace wall outwardly and mounted thereon adjustably, a sleeve around 45 said shaft having a segmentally spheric annulus around it, a pair of registering bearing elements with spheric hollow to receive said spheric annulus, one of the elements being clampingly connected to the other element to hold said annulus and sleeve with said rock-shaft in a desired position of adjustment relative to the wall part of the furnace casing upon which the bearing is mounted, and opposite connections between said shaft and the draft door and damper to operate them reversely.

2. In combination, a furnace having a draft door and a damper, a thermostatic device within the furnace including a rock-shaft projecting without the furnace and having a crank-arm with alined sheaves mounted in longitudinal alinement thereon, one sheave being mounted coaxially with said rock-shaft, said thermostatic device also in-

cluding a spring device of elements having different coefficients of expansion operating to rock the rock-shaft, a manually operable flexible device reeved to ride loosely upon opposite sides of said sheaves and connected to 70 said draft door and having end means for securing it to an anchoring device releasably, and an automatically operable flexible device connected to said damper and connected 75 adjustably to said crank-arm to vary the throw of said draft door.

In testimony whereof I affix my signature.
HOBART B. BROWN.
